UNITED STATES PATENT OFFICE.

JAMES C. GOOCH, OF PITTSBURGH, PENNSYLVANIA.

DEVICE FOR APPLYING LIQUIDS.

1,242,174.

Specification of Letters Patent.

Patented Oct. 9, 1917.

Application filed February 7, 1917. Serial No. 147,137.

To all whom it may concern:

Be it known that I, JAMES C. GOOCH, a citizen of the United States, and a resident of Pittsburgh, in the county of Allegheny and State of Pennsylvania, have invented a new and useful Improvement in Devices for Applying Liquids; and I do hereby declare the following to be a full, clear, and exact description thereof.

- 10 My invention relates to a device for applying solutions or liquids, and has special reference to such a device for use in applying medicinal solutions to wounds, cuts, etc. by means of streams or drops.
- 15 In the use of antiseptics or other solutions in connection with wounds, cuts, etc., such as the well-known Dakin-Carrel antiseptic solution, it has been applied to the wound continuously by streams or drippings from
- 20 catheters connected to the ordinary Y-tubes leading from the container for the solution, but in the case of the wound being long or of irregular, circular or angular shape, considerable difficulty would be experienced in
- 25 arranging such catheters, so as to apply the solution properly to the wounds or cuts.

The object of my invention is to overcome the above difficulty and to provide a cheap, simple and efficient device which will apply such liquids or solutions continuously to the wounds or cuts; and in a proper and even manner, so as to allow the wounds or cuts to receive the streams or drippings of the solution along the entire surface of the same,

35 regardless of their shape or size.

To these ends my invention consists, generally stated, in the novel arrangement, combination and construction of parts, as hereinafter more specifically set forth and described and particularly pointed out in the claims:

To enable others skilled in the art to which my invention appertains, to construct and use my improved device for applying solutions or liquids, I will describe the same more fully, referring to the accompanying drawing in which—

Figure 1 is a side elevation showing my improved device for applying liquids or solutions in position for operating. Fig. 2 is an enlarged vertical central section of the

device. Fig. 3 is a top view of the same, with the cover removed. Fig. 4 is a top view of the device. Fig. 5 is an enlarged detail view of a portion of the device. 55

Like symbols of reference herein indicate like parts in each of the figures of the drawing.

As illustrated in the drawing, *a* represents the fountain or container for holding the supply of liquid or solution to be used, which container is generally formed of glass and is adapted to be hung from any suitable support, such as by the chain *b* surrounding the same. The container *a* is provided with the tubular extension *c* at the bottom thereof and opening into the same. Fitting by its upper end over the extension *c* is a rubber tube *d* which is of sufficient length, and connects with the device or appliance 1 for applying 70 the liquid or solution, as hereinafter described.

The device or appliance 1 is provided with the base 2 of any suitable material such as rubber, which is preferably of circular form, and is adapted to set in a horizontal position in order to provide a flat upper surface 3 thereon. Engaging with the periphery of the base 2 is the top or cover 4, which is preferably of rubber, and is detachably connected to a threaded portion 5 on such periphery through a similar portion 6 on the lower end of such cover, said cover being of semi-spherical shape and being hollow in order to form the receptacle 7 between the same and said base when said cover is in position. Centrally from the upper portion of the cover 4 is the tubular extension 8, around which fits the lower end of the rubber tube *d*, and on either side of the said extension is a ring 9, which forms part of said cover and is adapted to be used to hold the appliance 1 in position out of a vertical line with the container *a* when desired by means of a cord or chain (not shown) connected thereto and to a wall or other suitable support. 90

Extending vertically through the base 2 are a series of openings or holes 10, and within each of said holes is a hollow supply 100 plug 11, which is formed of rubber, or other suitable material and the lower portions of

such plugs project through said holes. The lower ends of the plugs 11 are open and the upper ends of the same are closed and provided with a flared head 12, which is 5 adapted to fit within a countersunk seat 13 formed around the upper end of the holes 10 and in the flat upper surface 3 of the base 2. Within the upper ends of the plugs 11 and below the heads 12 thereon is an 10 opening 14 through the wall of such plugs and around the outer surface of the plugs is a threaded portion 15 for engaging with the walls of the holes 10.

In the use of my improved device for applying liquids or solutions, the usual rubber catheters 16 are connected at one end to the lower ends of each of the plugs 11, so that in using the same for the treating of wounds or cuts, the antiseptic solution is 20 placed within the container *a*, and will run down therefrom into the receptacle 7 in the appliance 1 through the tube *d* and fill up such receptacle. When it is desired to apply the solution, the plugs 11 can be grasped at 25 their lower projecting portions and by turning the same in the proper direction will be raised through the medium of the threaded portions 15 thereon, so that the heads 12 on such plugs will be unseated from 30 their seats 13 and thus allow the solution within the receptacle 7 to enter the openings 14 in such plugs and pass down through such plugs and catheters 16 into the wound or cut. The supply of the solution to the 35 catheters 16 can be closed or shut off by simply turning the plugs 11 in a reverse direction, which will allow such plugs to be screwed down, so that their heads 12 will be seated in the seats 13, and thus cover or 40 close the openings 14 in such plugs with the holes 10 of the base 2, thereby preventing the entrance of any of the solution from 45 the receptacle 7 into the plugs.

It will be obvious that my improved device for applying liquids, or solutions, can be used in connection with all kinds of wet dressings and any other liquids or solutions than those described, as well as for other 50 purposes, while various modifications and changes in the design, construction and operation of the device may be resorted to without departing from the spirit of the invention or sacrificing any of its advantages.

It will thus be seen that my improved device for applying liquids or solutions can be so arranged and nested that different shaped cuts or wounds can have an antiseptic dressing or solution applied by simply 55 opening certain supply plugs in the device, so that a selected number can be used to allow long or short straight cuts, circular, angular or irregular cuts, and other shapes, to be so treated or dressed. The horizontal

upper surface of the base of the receptacle 65 being flat, will permit a free and easy flow of the solution to the catheters, and the device will permit an even feed and even pressure in the flow of the solution. The device is antiseptic and sanitary, and the 70 parts are so constructed and arranged that they can be easily and readily kept clean at all times, while such device will not be liable to leak or get out of order.

What I claim as my invention and desire 75 to secure by Letters Patent is—

1. A device for applying liquids, comprising a base having a cover to form a receptacle between the same, a plurality of vertically arranged holes in said base, and a hollow plug within each of said holes and provided with a closed upper end and an open lower end, said plugs being adapted to be raised and lowered and having an opening in the upper end of the same for communicating with the receptacle in their raised positions. 80

2. A device for applying liquids, comprising a base having a cover to form a receptacle between the same, a plurality of vertically arranged holes in said base, and a hollow plug within each of said holes and provided with a closed upper end and an open lower end, said plugs having an opening in the upper end of the same for communicating 90 with the receptacle in their raised positions, and a threaded portion on said plugs engaging with the walls of said holes for raising and lowering the plugs. 95

3. A device for applying liquids, comprising a base having a cover to form a receptacle between the same, a plurality of vertically arranged holes in said base, a hollow plug within each of said holes and provided with an open lower end, said plugs being 100 adapted to be raised and lowered and having an opening in the upper end of the same for communicating with the receptacle in their raised positions, and a head for closing said 105 ends and for closing the plugs when in their lowered positions.

4. A device for applying liquids, comprising a base having a cover to form a receptacle between the same, a plurality of vertically arranged holes in said base, a hollow 115 plug within each of said holes and provided with an open lower end, said plugs being adapted to be raised and lowered and having an opening in the upper end of the same for communicating with the receptacle 120 in their raised positions, said holes having a seat around the upper end of the same, and heads on the upper ends of said plugs for closing said ends and for fitting in said 125 seats to close the plugs when in their lowered positions.

5. A device for applying liquids, comprising a base having a cover to form a recepta-

cle between the same, a plurality of apertures in said base, and valved tubular members mounted in said apertures.

6. A device for applying liquids, comprising a receptacle having a plurality of apertures in its base, and valved members mounted in said apertures, said members being adapted to communicate with said

receptacle when raised above the level of the base. 10

In testimony whereof, I the said JAMES C. GOOCH, have hereunto set my hand.

JAMES C. GOOCH.
